LOCK

Filed June 30, 1921

William J. Carroll
Henry E. Rockwell
Attorney

UNITED STATES PATENT OFFICE.

WILLIAM J. CARROLL, OF NEW HAVEN, CONNECTICUT, ASSIGNOR TO SARGENT & COMPANY, OF NEW HAVEN, CONNECTICUT.

LOCK.

Application filed June 30, 1921. Serial No. 481,605.

To all whom it may concern:

Be it known that I, WILLIAM J. CARROLL, a citizen of the United States, residing in the city and county of New Haven, State 5 of Connecticut, have invented certain new and useful Improvements in Locks, of which the following is a full, clear and exact description.

This invention relates to locks and more 10 particularly to improved controlling mechanism for the dead bolts or latch bolts of locks of the type employing winged keys. While my improvements may be found particularly useful with hotel locks or those 15 having similar uses, it will be apparent that they are not confined to this type of locks, but may be applicable to winged key locks of any description.

It has been the usual practice heretofore 20 to construct locks of this character in such a manner that a plurality of swinging or pivoted tumblers are provided to control the position of the bolt by engagement with a part of the bolt and which are in 25 turn controlled by the key bit. At the same time that the tumblers are moved to inoperative position or to a position to release the bolt, the key bit engages talons upon the bolt stem to protract or retract the bolt.

In the embodiment of my invention which I have illustrated in the accompanying 30 drawings, I have provided a lock mechanism having an operating or controlling slide which engages the bolt to control the same and which is in turn controlled by a suitable tumbler mechanism. It is to be noted, however, that in my improved construction this tumbler mechanism does not engage the slide itself, but on the contrary 35 engages and controls the position of a detent which in turn controls the position of the controlling slide. This detent is arranged to retain the controlling slide in either of its two extreme positions of movement and 40 the detent can only be moved from engagement with the slide when the tumblers have been actuated by the proper key. The key bit at the same time engages talons on the operating slide to impel this slide to its 45 various positions.

One object of my invention is the provision of an improved controlling mechanism for the bolt of the lock.

A further object of my invention is to

provide a controlling slide which may engage either the dead bolt or the latch bolt of a lock to control the same and which will be operated and in turn controlled by tumbler mechanism such as is at present used in connection with the bolt itself. 55

A still further object of my invention is to provide a detent to control the position of this controlling slide and to arrange the tumbler mechanism so that the position of this detent will in turn be controlled thereby. 60

Another object of my invention is to provide a lock of this character with tumbler mechanisms so arranged that it may be operated by a plurality of keys.

To these and other ends the invention 70 consists in the novel features and combinations of parts to be hereinafter described and claimed.

In the accompanying drawings:

Fig. 1 is a front elevational view of the 75 mechanism of a lock embodying my improvements, the front cover of the casing having been removed.

Fig. 2 is an enlarged sectional view substantially on line 2—2 of Fig. 5 of the operating mechanism of the lock; 80

Fig. 3 is a view similar to Fig. 2 showing the operation of the controlling mechanism as the bolt is being moved to protracted position; 85

Fig. 4 is a view similar to Fig. 2, but showing the controlling mechanism from the opposite side and is a section taken substantially upon line 4—4 of Fig. 5;

Fig. 5 is a sectional view on line 5—5 90 of Fig. 1;

Fig. 6 is a sectional view on line 6—6 of Fig. 1;

Fig. 7 is a sectional view on line 7—7 of Fig. 2; and

Fig. 8 is a perspective view of the bits of some of the keys adapted to be used with my improved lock.

While I have chosen to show my improved lock mechanism in connection with what is 100 commonly known as a mortise lock, it will be apparent that the principles of the invention may be equally applicable and useful in locks of other types. I have shown at 10 the usual lock casing in which is 105 mounted a latch bolt 11 having a stem 12 surrounded by a coil spring 13 which reacts against the shoulder on the forward

portion of the stem and against a pair of lugs 14 upon the lock case to normally protract the latch. Upon the rear end of the stem is mounted a cross-head 15, which may be engaged by a finger 16 upon a sliding yoke 17, operated by the usual roll-back 18 to retract the latch bolt when the door is to be opened. A coil spring 19 surrounding a stem in the sliding yoke normally maintains the yoke in its forward or inoperative position.

The dead bolt 20 is shown in this instance as mounted in the upper part of the casing 10 above the latch bolt and it is provided with a stem 21 of peculiar shape which projects upwardly toward the upper part of the casing and is provided with an arm 22 directed rearwardly in a generally horizontal direction. This arm 22 is provided with a notch 23 into which projects a controlling finger 24 which is a part of the operating slide of the controlling mechanism.

The controlling mechanism is designated as a whole by the numeral 25 and, as will be apparent, consists of the entire controlling mechanism for the bolt (in this instance the dead bolt) so mounted that it may be placed in the lock casing and removed therefrom as a unit without disturbing the parts heretofore described. The removable feature, however, of this controlling mechanism is not of importance as far as the particular invention described in this application is concerned, as the various parts of this mechanism may be permanently mounted within the lock case, if desired. This controlling mechanism in this instance consists of a frame composed of the two plates 26 and 27 connected by suitable posts 28, although the details of construction of this frame are not important and in the application of the broad principles of the invention, it may not be necessary to have a frame at all. This frame, is in the form shown, positioned within the lock casing by the plates 26 and 27 thereof being placed within depressions or wells 10^a and 10^b formed in the front and rear walls 50 of the lock casing, however, either suitable positioning or securing means may be provided, if desired.

Upon one of the posts 28 are pivoted a plurality of swinging tumblers 29 urged to their normal or lower position shown in Fig. 2 by suitable springs 30 which react against another of the posts 28. These tumblers are provided upon their forward faces with suitable recesses 31, the purpose 60 of which will be hereinafter explained.

The operating slide of the lock controlling mechanism is designated by the numeral 32 and is slidably mounted upon the frame by virtue of slots 33, 34 and 35 formed therein through which certain of the posts

28 project. Near the rear end of this slide are provided talons 36, which are adapted to be engaged by the bit 37 of the key. The slide, as has already been stated, carries the controlling finger 24 so that when the slide 70 is moved forwardly by the key, the bolt 20 will be protracted. A shoulder 38 is provided upon the forward lower corner of this slide and has a beveled upper surface 39 adapted to be engaged by a complementary surface 40 formed upon the lower portion of a swinging detent 41 pivotally mounted upon one of the posts 28. This detent is normally urged by the spring 43 into engagement with the shoulder 38.

This swinging detent is provided with a lug 42 which extends across the face of the tumblers, as is clearly shown in Figs. 5 and 6, and is adapted to be received in the recesses 31 in the face of the tumblers when these recesses are aligned and moved to the proper position by the key bit. When the tumblers are in this position, the pressure of the key bit upon the operating slide 32 will impart a forward motion to this slide, and due to the beveled upper surface of the shoulder 38, the swinging detent will be moved clockwise about its pivotal point, the lug 42 entering the recesses 31 and the lower portion 40 being moved upwardly a sufficient extent to allow the shoulder 38 of the slide to pass thereunder. The slide will then be moved forwardly by the key, the controlling finger 24 acting to protract the bolt.

The bolt stem may, if desired, be provided with a small tongue 44, which fits into a recess 45 in the operating slide 32 to provide a more secure connection between the bolt stem and slide.

It will be noted that the recesses 31 provided in the forward faces of the various tumblers 29 are so arranged that the tumblers may be moved to the proper position to permit movement of the detent 41 by a plurality of keys, for instance, both of the keys 50 and 51 shown in Fig. 8, may be used to operate the lock. The key shown at 51 may be termed a master key, as this key may be used to operate a plurality of locks of this type, only one of which may be operated by key 50.

It will be apparent that my improved controlling mechanism may be used in connection with a dead bolt, as shown, or the controlling finger may be mounted in position to dead lock the latch bolt, if desired. Such an arrangement is shown in my co-pending application Serial No. 481,604, filed June 30, 1921, and it will, therefore, be understood that when the term "bolt" is used in the specification and claims of this application, it is to be construed broadly as referring either to a latch bolt or to a dead bolt, as either may be controlled by the mechanism shown.

While I have shown and described some preferred embodiments of my invention, the same is not limited thereto in all of its details, but is capable of many modifications and variations which lie within the spirit of the invention and within the scope of the appended claims.

I do not claim herein a lock provided with a bolt and a removable swinging tumbler 10 controlling mechanism therefor, as this forms the subject matter of my copending application previously referred to.

What I claim is:

1. In a lock, a reciprocable bolt and means 15 to operate said bolt, including a reciprocable slide, said slide having a bolt operating finger projecting from one edge thereof, and a shoulder formed upon a face thereof, and a detent cooperating with said shoulder.

2. In a lock, a reciprocable bolt, and means to control said bolt comprising a reciprocable slide, said slide having a bolt engaging finger projecting from the upper edge thereof, and a shoulder provided upon 25 one face, and a detent to engage said shoulder.

3. In a lock, a reciprocable bolt and means to control the operation of the bolt comprising a reciprocable slide having a bolt 30 engaging finger projecting from the upper edge thereof, a shoulder formed upon the face of the slide adjacent the lower edge thereof, and a detent pivoted to swing across the face of the slide and engage said shoulder.

4. In a lock, a reciprocable bolt and means to operate said bolt comprising a reciprocable slide having means to engage said bolt, said slide having a shoulder formed 40 adjacent the lower edge thereof, a detent pivoted to swing across the face of the slide and engage said shoulder and tumbler mechanism to control said detent.

5. In a lock, a reciprocable bolt having a 45 head and stem and operating mechanism for the bolt, including a slide having a projecting finger, said bolt stem being offset to clear said operating mechanism and engage with said finger.

6. In a lock, a reciprocable bolt having a 50 head and stem and operating mechanism for the bolt disposed rearwardly of the bolt head, said stem being offset to clear the operating mechanism to prevent interference therewith.

7. In a lock, a reciprocable bolt having a head and stem and operating mechanism for the bolt, said mechanism being placed rearwardly of said head and said stem being offset upwardly to lie entirely above said operating mechanism.

8. In a lock, a reciprocable bolt having a head and stem and operating mechanism for the bolt disposed directly behind the head 65 thereof, including a reciprocable slide hav-

ing a bolt engaging finger at the upper edge thereof, said bolt stem being offset upwardly to clear said operating mechanism and engage with said finger.

9. In a lock, a lock case, a bolt reciprocably mounted therein, a plurality of supporting posts in said case, and controlling mechanism for the bolt including a bolt operating slide reciprocably mounted on the posts, and a slide controlling detent carried 70 by one of said posts.

10. A lock mechanism comprising a lock case, a reciprocable bolt mounted therein, supporting posts carried by the case, a slotted slide reciprocably mounted on the 80 posts, and controlling said bolt, and a detent pivoted on one of the posts and controlling said slide.

11. A lock mechanism comprising a lock case, a reciprocable bolt mounted therein, supporting posts within the case, a slide reciprocably mounted upon said posts and having a finger engaging the stem of the bolt, and a detent mounted on one of the 85 posts and controlling said slide. 90

12. A lock mechanism comprising a lock case, a reciprocable bolt mounted therein, supporting posts within the case, a slide reciprocably mounted upon said posts and having a finger engaging the stem of the 95 bolt, and a projecting shoulder upon one face thereof, and a detent mounted upon one of the posts to engage said shoulder to control the operation of the slide.

13. A lock comprising a bolt, a movable 100 detent to control the operation of the bolt, a projection on said detent, and key actuated tumblers resting upon and having a part normally lying in the path of said projection to prevent movement of the 105 detent to inoperative position.

14. A lock comprising a bolt, an operating slide to control the bolt, a movable detent normally retaining said slide in a given position, and tumblers resting at one end upon said detent and normally lying in the path of movement of the detent to prevent movement thereof to inoperative position. 110

15. A lock comprising a bolt, an operating slide to control the bolt, a movable detent 115 normally retaining said slide in a given position, a projection on said detent, and key-actuated tumblers resting upon and having a part normally lying in the path of said projection to prevent movement of said detent to inoperative position, said tumblers being movable to position to clear said detent. 120

16. A lock comprising a bolt, an operating slide to control the bolt, a movable detent 125 normally retaining said slide in a given position, a projection formed on said detent and key-actuated tumblers resting upon and normally engaging said projection to prevent movement of said detent to inoperative 130

position, said tumblers being provided with recesses to clear said detent when actuated by the proper key.

17. A lock comprising a bolt, an operating slide to control the bolt, a movable detent normally retaining said slide in a given position and key-actuated tumbler mechanism supported at one end by said detent to prevent movement of the latter to inoperative position and means on said slide to move said detent from retaining position when such movement is permitted by said tumblers.

18. A lock comprising a bolt, an operating slide to control the bolt, a movable detent normally engaging a part of the slide to retain the latter in a given position, tumblers supported at one end by and normally preventing movement of said detent, means upon said slide to move said detent to inoperative position when said tumbler mechanism and slide are actuated by the proper key.

19. A lock mechanism comprising a case, a bolt reciprocably mounted in the case, and

operating means for the bolt comprising a reciprocable slide, tumbler mechanism to control said slide and a detent movably mounted between said tumbler mechanism and said slide for cooperation with both of 30 said parts.

20. A lock mechanism comprising a reciprocable bolt and operating mechanism for the bolt, including a reciprocable slide, tumblers mounted to swing across the face of 35 the slide, a detent pivotally mounted between said tumblers, and slide, said detent having means to engage the bolt and other means to engage the tumbler mechanism.

21. In a lock, a lock case, a bolt reciprocably mounted therein, and means to operate the bolt comprising a reciprocable slide, a plurality of tumblers pivotally mounted in the case, and means to control said slide by said tumblers including a 40 detent pivoted to swing between said tumblers and said slide.

In witness whereof, I have hereunto set my hand this 27 day of June, 1921.

WILLIAM J. CARROLL.
